UNITED STATES PATENT OFFICE

KIRBY T. PENICK AND ARTHUR J. PENICK, OF HOUSTON, TEXAS

PUMP

Application filed February 28, 1928. Serial No. 257,616.

This invention relates to new and useful improvements in a pump. One object of the invention is to provide in a pump, a novel type of traveling valve of such construction as to keep the inner wall of the working barrel comparatively free of sand and grit to the end that the traveling valve will not be quickly worn out by such sand and grit.

Another object of the invention is to provide a pump traveling valve of such construction that it will not readily wear and leak, and will not readily wear the working barrel in which it works.

A further object of the invention is to provide, in a pump, a traveling valve having a novel arrangement of cup rings disposed to keep the inner wall of the works barrel free of sand and grit and also having upwardly directed fluid discharge openings disposed to direct the fluid being pumped upwardly and outwardly against the walls of the working barrel, above the traveling valve to keep said walls clean and thus lessen the wear on said valve.

With the above and other objects in view this invention has particular relation to certain novel features of construction, operation and arrangement of parts an example of which is given in this specification and illustrated in the accompanying drawings, wherein:

Figure 1 shows a fragmentary vertical sectional view of a pump showing the upper end of the traveling valve.

Figure 2 shows a vertical sectional view of an intermediate section thereof.

Figure 3 shows a side view, partly in section, of the lower end of the traveling valve, and the associated pump barrel, which is shown in section, and

Figure 4 shows a vertical sectional view of the lower end of the pump with the standing valve therein.

Referring now more particularly to the drawings, wherein like numerals of reference designate similar parts in each of the figures the numeral 1 designates the pump barrel whose lower end has a downwardly converging seat 2 therein, in which a downwardly tapering valve body 3 is seated and

secured. This valve body is of conventional construction and has the upwardly opening ball valve 4 associated therewith which controls the fluid passageway therethrough and which is confined by the cage 5 which is attached to the upper end of the body 3.

Above the standing valve there is a novel type of reciprocable traveling valve which will now be described: This traveling valve includes a tubular body 6, preferably of brass and which fits closely within the barrel 1. Attached to the upper end of the body 6 there is a tubular valve casing 7, whose outside diameter is somewhat less than the inside diameter of the barrel 1 so as not to contact therewith. Within the lower end of this casing 7 there is secured an annular valve seat 8 which is controlled by the upwardly opening ball valve 9. Within the casing 7 and spaced above the valve 9 there is a depending tubular thimble 10 having lateral ports 11 and whose lower end is flared to form a seat 12. Upon downward movement of the traveling valve the ball valve 9 is lifted by the fluid and seated against the seat 12 but the fluid can pass on up through the thimble ports 11. This thimble 10 thus prevents the ball valve 9, upon being lifted, from entirely or partly blocking the fluid passageway up through the traveling valve and forms a means for such purpose which will not be readily worn out. Attached to the upper end of the valve cage 7 there is a tubular nipple 13 whose upper end is closed and reduced and outwardly threaded as at 14 thus forming a connection for the sucker rod through which the traveling valve may be reciprocated. On this nipple 13 there is a series of cup rings 15 whose open ends are directed upwardly and which are spaced apart by means of the spacer rings 16, disposed between them. These cup rings and spacer rings are clamped together in assembled relation by means of the external annular shoulder 17, on the nipple 13, against which the upper cup ring abuts, and against which the lock nut 18 threaded onto the lower end of the nipple 13 which abuts the lower cup ring.

The upper ring 15 is reinforced, and held firmly against the inner wall of the working

barrel 1 by means of the cup shaped, inside, metallic reinforcing ring 19. Above the cups 15 the nipple has a plurality of series of upwardly and outwardly directed fluid discharge passageways 20 disposed to direct the pumped fluid upwardly against the barrel walls above the traveling valve to wash said walls clean. Attached to the lower end of the body 6 there is the bottom tubular nipple 21 whose outside diameter is some what less than the inside diameter of the barrel so as not to contact therewith. On the upper end of the nipple 21 there is an annular valve seat 22 which is controlled by the upwardly opening ball valve 23. This valve 23 is located in an enlarged chamber 24, in the lower end of said body 6 and is confined, in its upward movement by the cross rod 25. The upper portion of the nipple 21 is hexagonal to receive a wrench and the nipple 21 is reduced beneath this portion forming an annular downwardly facing shoulder 26 against which the upper one of a series of cup rings 27, abuts. These cup rings are arranged on the reduced portion of the nipple 21 and their open ends face downwardly and they are spaced apart by the spacer rings 28. These rings 27, 28 are held in assembled relation against the shoulder 26 by the ring nut 29 which is threaded on the lower end of the nipple 21 and abuts the lower spacer ring 28.

In operation on upward movement of the traveling valve the ball valves 9 and 23 will be closed and the standing valve will open 35 and the fluid from beneath will be drawn into the working barrel. The cup rings 15, upon such upward movement will sweep the grit and sand from the inside wall of said working barrel so that the traveling valve body 6 will not be cut away thereby. Upon downward movement of the traveling valve the standing valve will close and the ball valves 9 and 23 will be lifted and the fluid being pumped will pass above the traveling 45 valve. Said fluid will be discharged in streams through the passageways 20 against the walls of the barrel 1 and will wash the sand and grit off the walls of said barrel in advance of the cup rings 15. The cups 27, 50 upon downward movement, will clean the inner walls of the barrel 1 of grit and sand to prevent the body 6 from being worn thereby.

The nipples 7 and 21 are made of corrosive material but in case they become corroded and pitted by the acid in the fluid they will not score or wear the working barrel inasmuch as they are not in contact therewith.

It is obvious that mechanical changes may be made and equivalents substituted for the 60 parts shown and the right is reserved to make such changes and substitutions as may be found desirable and such as may be comprehended within the scope of the appended claims.

65 What we claim is:—

1. A traveling valve including a tubular body, a tubular valve casing attached to the upper end of said body, a valve seat in the lower end of the casing, an upwardly opening valve controlling said seat, a depending tubular thimble within the casing and spaced above said valve whose lower end is provided with a valve seat, said thimble having a lateral port above said lower end, a tubular nipple attached to the upper end of said cage 70 whose upper end is reduced forming a connection for a sucker rod, a series of cup rings on said nipple whose open ends are directed upwardly and which are spaced apart, means on the nipple between which said cup rings are clamped, said nipple being provided with a series of upwardly and outwardly directed fluid discharge passageways above said cup rings, a bottom tubular nipple attached to the lower end of said body, a valve seat at the 75 upper end of said bottom nipple, an upwardly opening valve controlling said last mentioned valve seat, a series of cup rings around said bottom nipple with their open ends facing downwardly and means for clamping said 80 cup rings of said bottom nipple.

2. A traveling valve including a tubular body, a tubular valve casing attached to the upper end of said body and whose outside diameter is less than that of said body, a valve 85 seat in the lower end of the casing, an upwardly opening valve controlling said seat, a depending tubular thimble within the casing and spaced above said valve whose lower end is provided with a valve seat, said thimble having a lateral port above said lower end, a tubular nipple attached to the upper end of said cage whose upper end is reduced forming a connection for a sucker rod, a series 90 of cup rings on said nipple whose open ends are directed upwardly and which are spaced apart, means on the nipple between which said cup rings are clamped, a metallic reinforcing ring within the upper cup ring, said nipple being provided with a series of upwardly and outwardly directed fluid discharge passageways above said cup rings, a bottom tubular nipple attached to the lower end of said body whose outside diameter is less than that of such body, a valve seat at 95 the upper end of said bottom nipple, an upwardly opening valve controlling said last mentioned valve seat, a series of cup rings around said bottom nipple with their open ends facing downwardly, and means for 100 clamping said rings of said bottom nipple.

In testimony whereof we have signed our names to this specification.

KIRBY T. PENICK.
ARTHUR J. PENICK.
